UNITED STATES PATENT OFFICE.

GEORGE T. LADD, OF PITTSBURGH, PENNSYLVANIA.

BOILER-SETTING.

1,159,051.

Specification of Letters Patent.

Patented Nov. 2, 1915.

Application filed November 14, 1914. Serial No. 872,224.

To all whom it may concern:

Be it known that I, GEORGE T. LADD, residing at Pittsburgh, in the county of Allegheny and State of Pennsylvania, a citizen of the United States, have invented or discovered certain new and useful Improvements in Boiler-Settings, of which improvements the following is a specification.

The invention described herein relates to 10 certain improvements in settings for boilers of the water tube type having upper and lower drums, and has for its object a construction wherein the boiler is supported by a metal frame wholly independent of the 15 inclosing brick walls which however are firmly braced externally by the metal frame.

The invention is hereinafter more fully described and claimed.

In the accompanying drawings forming a 20 part of this specification, Figure 1 is a front view partly in section showing my improved setting; Fig. 2 is a side elevation of the same; Fig. 3 is a sectional elevation, the plane of section being indicated by the lines 25 III—III Fig. 1; Fig. 4 is a view partly top plan and partly in section; Fig. 5 is a detail view illustrating a modification of the manner of supporting the upper drum; Fig. 6 is a sectional view on a plane indicated by 30 the line VI—VI Fig. 5; Fig. 7 is a sectional view illustrating a modification in the support for the front wall of the setting; Fig. 8 is an enlarged detail view of one of the 35 supporting columns, Fig. 9 shows enlarged plan and section of the supporting fingers; Fig. 10 is a sectional detail showing the cushioning of the ends of a lower drum in one of the side walls.

In the practice of my invention, columns 40 or posts 1 are provided preferably having one side, as *a*, channel shaped, either rolled or built up, and a side at right angles to the first, formed by a plate *b* riveted to one of the angles of the channel shape. The invention 45 however is not limited to any particular construction of said columns which however have two sides at an angle to each other so as to inclose the angles formed by the back and side walls of the setting. In order 50 that the channel members of the columns at the rear corners of the setting may bear firmly against the side walls of the setting, the plate members *b* of the columns are tied together, the connecting part or 55 parts extending between the columns across the back wall of the setting. When it is not

necessary to protect or armor this back wall, the columns may be tied together by rods 2 engaging at their respective ends angular clips 3 riveted to the rear side walls or plates 60 *b* of the columns. To the upper ends of these columns are secured ends of horizontal girders 4 of any suitable construction and extending forward to the front corners of the portion of the setting forming the heating chamber, which incloses the boiler. The front ends of these girders are riveted to the upper ends of vertical supports and the upper portions 5 of said supports are preferably channel shapes which may be built up 65 or rolled. The lower portions of these supports 5 form the outer faces or armor of the side walls of the fire chamber of the setting as shown in Fig. 2. These outer faces, which laterally support the brick work of 70 the side walls of the fire-chamber, are formed of metal plates reinforced by vertically arranged angles 6 riveted to the plates. As shown in Fig. 2 the side armor of the fire-chamber and the vertical extensions 5 75 thereof are tied to the channel portions *a* of the columns 1 by any suitable means known in the art. As for example when it is not deemed desirable or necessary to protect or armor the side walls of the heating 80 chamber of the setting, the side armor of the fire chamber and the extensions 5 thereof may be tied to the columns 1 by rods 7 arranged at suitable intervals below the girder 4. The vertical supports 5 are connected at their upper ends by an angle bar 8, and at an intermediate point by a channel 9 as shown in Fig. 1. The front wall of the fire-chamber is protected and laterally supported by a metal plate 10 which may be 85 formed in sections and is reinforced by a series of angle bars 11 extending horizontally across the plate and riveted thereto as shown in Fig. 1. The sides of this front armor are riveted to one side of angles 6 reinforcing the side plating or armor of the fire-chamber.

As clearly shown in Fig. 2, the upper edges of the girders 4 are cut away to form concave recesses for the reception of the upper drum 12 to which the upper ends of the tubes 13 are connected, the lower ends of the latter being in turn connected to the lower drum 14 as is the usual practice. The saddles 15 in which the drum rests are formed 100 by metal pieces secured to the girder along 105 the edges of the concave recesses.

It will be observed that the girders forming the immediate support for the upper drum and through the latter for the entire boiler structure, are included and form a part of a rigid metal structure which surrounds and braces but does not engage or interlock with the brick work as will hereinafter appear. It will be understood that although the improvement is described and shown in connection with a two drum boiler, *i. e.*, one upper and one lower drum, that by merely increasing the dimensions of the parts of the metal frame and providing additional saddles on the girders, the improvements can be used with any desired size of boiler, requiring a plurality of upper drums.

The walls forming the fire-chamber and the heating chamber in which the boiler is suspended, as described, are made double, the exterior portion 16 being formed of ordinary brick and the interior portion 17 of fire brick, where required. The inner and outer sections of the walls are closely in contact for their entire extent but are not bonded together in any way, so that each can move independent of the other according to their different expansions. It will be seen especially in Figs. 1, 3 and 4, that while the parts of the metal frame will bear firmly against the outer wall, that no portion of the frame projects into said walls or otherwise engages them, and hence the movement of the frame or the wall, which has a different rate of expansions than the frame, will not tend to rupture the wall, and thereby form cracks through which air might enter.

The fire-chamber may, according to its dimensions, be divided into sections, two or more, by suitable partitions 18. The fire-chamber or sections thereof are closed on top by one or more arches 19, the inner ends of which are flush with the inner surface of the front wall of the heating chamber. As these arches have not sufficient strength to support the front wall of the setting and are subjected to high temperatures and are thereby rapidly weakened, provision is made for supporting the front wall of the heating chamber independent of these arches. To this end a girder 20 formed of oppositely facing channel bars, is arranged across and immediately above the arches 19 the ends of said girder projecting through openings 5 in the vertical supporting members 5, as shown in Figs. 1, 2 and 3. By arranging the channel bars with their flanges projecting inwardly as shown in Fig. 3, a box-like open-ended girder 20 is formed, and by forming openings 21 through the web of the outer channel, air will circulate through the girder and prevent its becoming unduly heated and thereby weakened. This girder is made of sufficient width to support the outer portion 16 of the front wall of the set-

ting. The inner portion 17 of the wall is supported by a series of inwardly projecting fingers 22 secured to the girder. While the fingers may be attached to the girder by any suitable means, a convenient construction for that purpose consists of bolts 23 passing through the fingers and blocks 24 inside the girder as shown in Fig. 3. In order to permit of the removal of a finger and the insertion of a new one, openings *c* a little larger than the heads of the bolts 23 are formed through the fingers and slots *d* extending from these openings longitudinally of the fingers as shown in Fig. 9. It is preferred that the fingers should be recessed as *c* adjacent to the slots for the reception of the heads of the bolts. When replacing a finger, the workman can reach through a hole 21 in the front wall of the girder 20 and loosen the nuts on the bolts 23 sufficiently to permit the finger being shifted longitudinally until the head of the bolt is in line with the opening *c*, whereupon the bolt can be withdrawn and the finger entirely removed. A new finger can be placed in position by a reversal of the above operations. While it is preferred to secure the fingers on top of the girder as shown in Fig. 3 in which case the girder will be protected by secondary arches 24 above the inner ends of the arch 19, the fingers may be secured to the under-side of the girder as shown in Fig. 7 in which case the latter will be protected by the inner fire brick wall 17 resting on the fingers.

As shown in Figs. 5 and 6 the upper drum may be so supported as to be wholly within the girders 4, by securing lugs 25 on the ends of the drum, said lugs being adapted to rest on the girders. These lugs may be formed by bending an angle or in any other suitable manner and riveting it to the ends of the drum, in which case the lugs would rest in saddles on the girder as hereinbefore described.

As shown in Fig. 1 the inner and outer portions of the side walls of the heating chamber do not extend to the drum and lower edges of the girders respectively, but are stopped short sufficient distances to permit of the expansive movements of the wall without effecting the metal frame or drum. The spaces thus left for expansion are filled with asbestos as shown at 25, which will yield as the wall moves.

As shown in Fig. 10 the ends of the lower drum project into recesses formed in the side walls of the heating chamber. These recesses are made sufficiently larger than the drum and the spaces thus provided are filled with yielding material as asbestos 27, thus providing for the independent movements of the drum and side walls.

It is characteristic of my improved setting including heating and fire chambers

that it is rectangular in cross-section and that as no part of the supporting frame is inclosed to any extent in the brickwork, the inclosing structure can be formed of whole brick, thereby facilitating the erection, preventing waste through broken brick, and insuring a more completely sealed and permanent structure.

I claim herein as my invention:

10 1. The combination of a metal frame consisting of vertical and horizontal members, the latter forming ties connecting the vertical members, girders secured to the vertical members, a boiler consisting of an upper drum and parts suspended therefrom, said drum so supported by the girders that a portion of the drum will project above the girder, walls arranged within but independent of the vertical and horizontal members, whereby said walls and members may move independent of each other with changes of temperature.

2. In a boiler setting, the combination of a boiler having a drum and parts suspended therefrom, a metal-frame adapted to support the drum, double walls arranged within the metal frame and inclosing the boiler, the metal frame and inner and outer walls being unconnected the one with the other.

30 3. In a boiler setting, the combination of walls forming the heating and fire-chambers, a metal frame arranged outside but independent of said walls and forming lateral supports therefor, a girder arranged horizontally above the fire-chamber having its ends supported by vertical members of the frame and adapted to support the wall of the heating chamber on the side connected with the fire-chamber, and a boiler supported by the frame and extending down into the heating chamber.

4. In a boiler setting, the combination of a metal frame arranged outside of said walls and forming lateral supports therefor, a girder arranged horizontally above the fire-chamber having its ends supported by vertical members of the frame, and adapted to support the outer portion of the front wall of the heating chamber, fingers secured to the girder and adapted to support the inner portion of said wall and a boiler supported by the frame and extending down into the heating chamber.

5. In a boiler setting, the combination of walls forming the heating and fire chambers, a metal frame arranged outside but independent of said walls and forming lateral supports therefor, a hollow girder having openings for the circulation of air therethrough arranged horizontally above the fire-chamber and having its ends supported by vertical members of the frame and adapt-

ed to support the wall of the heating chamber on the side connected with the fire-chamber, and a boiler supported by the frame and extending down into the heating chamber.

6. In a boiler setting, the combination of brickwork arranged to form a horizontally rectangular inclosure, posts or columns constructed to bear against the outer surfaces of the brickwork at the corners of the inclosure, ties connecting the post or columns inclosing adjacent corners of the inclosure, a boiler consisting of a drum and parts suspended therefrom, and members carried by the columns for supporting the boiler within the brickwork out of engagement with any portion thereof.

7. In a boiler setting, a horizontally rectangular inclosure, including a fire and a heating chamber and formed of brickwork, metal columns or posts adapted to inclose the corners of the brickwork, ties connecting adjacent columns or posts, the frame consisting of the columns and ties being adapted to maintain the rectangular contour of the brickwork but movable independent of the latter, and a boiler arranged within the heating chamber and supported by the metal frame independent of the brickwork.

8. In a boiler setting, the combination of brickwork forming an inclosure for the boiler, vertical columns in line with a side wall of the inclosure, a hollow girder having its ends extending through such columns and serving to support the side wall intermediate the vertical columns.

9. In a boiler setting, the combination of a horizontally arranged girder forming a portion of a side wall of the setting, a series of fingers projecting inwardly from the girder, and brickwork forming the boiler inclosure, a wall of said brickwork having its outer portion supported by the girder and its inner portion by the inwardly projecting fingers.

10. In a boiler setting, the combination of a horizontally arranged girder forming a portion of a side wall of the setting, a series of independently removable fingers secured to the underside of the girder, brickwork forming the boiler inclosure, wall of inclosure having its outer portion supported by the girder and its inner portion extending down alongside of the girder and supported by the fingers.

In testimony whereof, I have hereunto set my hand.

GEORGE T. LADD.
